Primary Examiner—T. Chase Nelson*Assistant Examiner*—Karen Acker*(74) Attorney, Agent, or Firm*—Nixon & Vanderhye, PC(57) **CLAIM**

The ornamental design for a “packaging tray with apertures,” as shown and described.

DESCRIPTION

FIG. 1 is a perspective view of a packaging tray with apertures showing my new design;

FIG. 2 is a top plan view thereof;

FIG. 3 is a front elevational view thereof, the rear elevational view being a mirror image thereof;

FIG. 4 is a right side view thereof, the left side view being a mirror image thereof;

FIG. 5 is a bottom plan view thereof; and,

FIG. 6 is a plan view of the packaging tray with apertures of FIG. 1 in an unassembled condition.
